UNITED STATES PATENT OFFICE.

THOMAS J. LITTLE, JR., OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

DESIGN FOR A GAS-BURNER.

No. 38,955.

Specification for Design.

Patented Dec. 17, 1907.

Application filed October 27, 1906. Serial No. 340,925. Term of patent 14 years.

To all whom it may concern:

Be it known that I, THOMAS J. LITTLE, Jr., of Gloucester City, Camden county, New Jersey, have invented a new, original, and ornamental Design for a Gas-Burner, reference being had to the accompanying drawing, forming part of this specification, which is a perspective view of a gas-burner embodying my design.

I claim:—
The ornamental design for a gas burner, as shown.

THOMAS J. LITTLE, JR.
